US00D962921S

(12) **United States Design Patent** (10) Patent No.: **US D962,921 S**
(45) Date of Patent: ** Sep. 6, 2022

(54) **LAPTOP COMPUTER**

(71) Applicant: **Quanta Computer Inc.**, Taoyuan (TW)

(72) Inventors: **Chee-Chun Leung**, Taoyuan (TW);
Wen-Hung Tsai, Taoyuan (TW);
Chang-Ta Miao, Taoyuan (TW);
Gwo-Chyuan Chen, Taoyuan (TW);
Chih-Kang Ting, Taoyuan (TW);
Shun-Kai Chuang, Taoyuan (TW)

(73) Assignee: **QUANTA COMPUTER INC.**,
Taoyuan (TW)

(**) Term: **15 Years**

(21) Appl. No.: **29/724,153**

(22) Filed: **Feb. 13, 2020**

(30) **Foreign Application Priority Data**

Oct. 31, 2019 (TW) 108306731

CLAIM

The ornamental design for a laptop computer, as shown and described.

DESCRIPTION

FIG. 1 is a top, front and right perspective view of a laptop computer in an unfolded state, showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a top, front and right perspective view of the laptop computer of FIG. 1, shown in an alternate configuration of use;

FIG. 9 is a top, front and right perspective view of the laptop computer of FIG. 1, shown in another alternate configuration of use;

FIG. 10 is a top, rear and left perspective view thereof; and, FIG. 11 is a top, front and right perspective view of the laptop computer of FIG. 1, shown in another alternate configuration of use.

The broken lines in FIG. 7 depict portions of the laptop computer that form no part of the claimed design.

1 Claim, 11 Drawing Sheets
